2 SHEETS-SHEET 2.

UNITED STATES PATENT OFFICE.

GEORGE A. TURNER, OF NEW ORLEANS, LOUISIANA.

WATER-COOLER.

No. 901,663.

Specification of Letters Patent.

Patented Oct. 20, 1908.

Application filed November 15, 1907. Serial No. 402,319.

To all whom it may concern:

Be it known that I, GEORGE A. TURNER, citizen of the United States, residing at New Orleans, in the parish of Orleans and State of 5 Louisiana, have invented certain new and useful Improvements in Water-Coolers, of which the following is a specification.

My invention relates to certain new and useful improvements in water coolers, and 10 the object of my invention is to produce a cooler which is cheap, sanitary and efficient.

With these objects in view my invention consists in certain constructions, combinations and arrangement of parts the preferred 15 form of which will be first described in connection with the accompanying drawings and then the invention particularly pointed out in the claims.

Referring to the drawings wherein I show 20 the preferred form of my invention and wherein the same part is designated by the same reference numeral wherever it occurs, Figure 1 is a perspective view of my cooler with the parts in their normal position; Fig. 25 2 is a central longitudinal section showing the reservoir as tipped back to the position where access to the ice chamber may be had; Fig. 3 is a detail sectional view; and Fig. 4 is a detail fragmentary view showing the 30 support for the water reservoir.

1 designates a hollow base provided with an outlet valve 2. This base forms the waste pan and is adapted to hold the water which runs off from the ice.

35 3 designates the outer wall of the main or cooling chamber and 4 the inner wall thereof, the space between the walls being filled by any suitable packing as 5.

The bottom 6 of the chamber has passing 40 centrally therethrough the screw threaded hollow plug 7, provided with a central perforation 8, into which a screw threaded projection 9 of the ice containing pail 10 is adapted to engage, whereby an open waste 45 pipe is formed from the ice pail to the waste pan.

The cooling chamber formed by the walls 3 and 4 is provided at the top with the inwardly projecting flange 11, which is bent 50 down and is then formed into an inwardly projecting lip 12 on which the outwardly bent flange 13 of the ice pail is adapted to rest and by which the ice pail is supported in position.

55 14 designates an ordinary bail for the pail by which the pail may be removed.

15 is a cover suitably hinged to the flange 11 and adapted to cover the top of the pail when the same is in position. It will be noted that there is a space between the inner 60 wall 4 and the pail 10 in which water is adapted to pass as will be hereinafter described, water being confined therein in a comparatively thin layer whereby it is readily cooled.

40 is a drawoff faucet of any desired construction whereby the water is drawn from the chamber.

16 is the water reservoir which is pivoted at 17 to the upper edge of the main portion of the cooler. This reservoir is preferably of 70 the form best shown in Figs. 1 and 2, and is provided at its top with an opening 17, around which projects the flange 18, to one side of which is hinged the cover 19, this opening forming the filling opening for the 75 reservoir with which the cover makes an airtight joint when closed.

20 designates a guide way, preferably formed by bending up a strip of sheet metal in the form best shown in Fig. 4. This guide 80 way is closed at its upper end by the end plate 21, and has the slot through the length thereof narrower than the main portion of the guide.

22 is a rod pivoted to the bracket 23 85 mounted on the base, and at its upper end the rod is provided with the laterally projecting fingers 24, which are adapted to enter the guide 20. This rod and guide form a support for the reservoir when it is tilted into the position shown in Fig. 2. At the bottom of the reservoir I provide a projecting flange 25 which, at the front portion, is cut away as shown at 26.

In the bottom 27 of the reservoir I provide 90 an opening 28, in which I secure the oblong valve casing 29, the casing extending both above and below the bottom 27. Within the reservoir the casing at its upper end is provided with a cap 30 and in its side are a 100 series of perforations 31. The lower end of the casing is rounded as shown, and is provided with an opening 32 controlled by the capsule shaped valve 33, which is normally pressed against the opening by the 105 spring 34, one end of which is secured to the cap 30 of the casing, and the other end of which passes within the capsule.

35 is a rod projecting from the end of the valve 33 through the opening 32.

36 is an opening cut in the flange 11 and of the same size as the valve casing 30, into

which, when the parts are in their normal position shown in Fig. 1, the valve casing projects.

37 is a shelf projecting out below the opening 36 against which the end of the rod 35 contacts when the parts are in their normal position, as is best shown in Fig. 3, thus operating to open the valve. The outside of the valve casing 29 is preferably threaded, and mounted on this threaded portion is a ring 38, which is adapted to force a rubber gasket 39 into contact with the edges of the opening 36, so as to make a tight joint between the valve casing and the flange 11, whereby air drawn into the cooling chamber has to pass around the upper edge of the ice pail when water is drawn from the cooling chamber, whereby the water will not flow as freely from the spigot 40.

20 In the operation of my device the reservoir 16 is filled through the opening 17, and then the cap 19 closed. This cap should fit the flange 18 so as to form a tight joint. When the ice pail is to be filled the reservoir 25 is thrown back into the position shown in Fig. 2, when the lid 15 may be lifted and the ice pail filled. To place the device in operative position the reservoir is swung down until it assumes the position shown in Fig. 1, when 30 the valve casing, entering the opening 36, makes connection between the reservoir and the cooling chamber, the pin 35 striking against the valve 37 opens the valve and permits the water to pass into the cooling chamber. It will of course be understood from 35 an inspection of Fig. 3, that when the parts are in this position, the end of the valve casing 29 having the opening 32 therein is below the horizontal plane of the flange 12, and 40 consequently below the top of the ice pail, so that as soon as the water in the cooling chamber covers the opening 32 no more water can flow from the reservoir 16 into the cooling chamber until some has been drawn 45 off by the faucet 40. From this it will be seen that as long as any water remains in the reservoir the cooling chamber will be kept full to the level of the opening 32. In order to make a tight fit between the parts the ring 50 38 may be adjusted on the valve casing to force the gasket against the edges of the open-

ings 36. This can be readily done through the cut away portion 26 in the flange 25.

To remove the ice chamber for purposes of cleaning, the operation just described is reversed, and then by taking hold of the handle 14 the ice pail can be revolved to disconnect the parts 7 and 8, which must be done before the pail can be removed.

While I have described what I believe to be the preferred form of my invention, I desire to have it understood that many changes can be made in the form, construction and arrangement of parts without departing from the spirit of my invention.

What I claim as new and desire to secure by Letters Patent is

1. In a cooler, the combination with the cooling chamber, of an ice container removably seated therein, said container having a screw threaded pipe extending therefrom, a screw threaded connection passing through the bottom of the cooling chamber with which the screw threaded pipe is adapted to be connected, and a reservoir mounted above the cooling chamber and adapted to be connected thereto by an air tight joint.

2. In a cooler, the combination with a cooling chamber, of an ice chamber removably mounted within the cooling chamber, a reservoir hinged to one side of the cooling chamber, an outlet valve for the reservoir and means for effecting an air tight joint between the valve and the cooling chamber.

3. In a cooler, the combination with a cooling chamber, of a reservoir hinged to one side of the top of the cooling chamber, the reservoir being provided with an opening in its bottom, a valve casing fitted in the opening, said valve casing extending above and below the bottom of the reservoir, perforations through the portion of the casing within the reservoir, a valve located in the portion of the casing outside the reservoir and means for opening said valve when the reservoir and cooling chamber are connected.

In testimony whereof I affix my signature in presence of two witnesses.

GEORGE A. TURNER.
